Des. 240,769
Patented July 27, 1976

240,769

CONTAINER FOR COSMETICS

Arleen Bowman, 302 W. 12th St.,
New York, N.Y. 10014

Filed Jan. 16, 1975, Ser. No. 541,635

Term of patent 14 years

Int. Cl. D3—99

U.S. Cl. D86—10 N

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 1 is a top perspective view of a container for cosmetics showing my new design;

FIG. 2 is a bottom perspective view thereof;

FIG. 3 is a front elevational view thereof;

FIG. 4 is a rear elevational view thereof;

FIG. 5 is a top plan view thereof;

FIG. 6 is a side elevational view thereof;

FIG. 7 is a top perspective view of a second embodiment of the design shown in FIG. 1;

FIG. 8 is a bottom perspective view of the embodiment shown in FIG. 7;

FIG. 9 is a front elevational view thereof;

FIG. 10 is a rear elevational view thereof;

FIG. 11 is a top plan view thereof; and

FIG. 12 is a side elevational view thereof.

I claim:

The ornamental design for a container for cosmetics, as shown and described.
